UNITED STATES PATENT OFFICE

134,956

DESIGN FOR A COMBINED SHAVING CUP AND RAZOR BLADE HONE

Richard W. Harrison and Frank Grabowski,
Charlestown, Mass.

Application May 25, 1942, Serial No. 167,092

Term of patent 3½ years

To all whom it may concern:

Be it known that we, Richard W. Harrison, a citizen of the United States and residing at 106 Washington Street, Charlestown, in the county of Suffolk and State of Massachusetts, and Frank Grabowski, a citizen of Poland and residing at 106 Washington Street, Charlestown, in the county of Suffolk and State of Massachusetts, have invented a new, original, and ornamental Design for a Combined Shaving Cup and Razor Blade Hone, of which the following is a specification, reference being had to the accompanying drawing, forming a part thereof.

Figure 1 is a top view of a combined shaving cup and razor blade hone showing our new design; Figure 2 is a side elevational view thereof; and Figure 3 is a rear elevational view thereof.

We claim:

The ornamental design for a combined shaving cup and razor blade hone, substantially as shown.

RICHARD W. HARRISON.
FRANK GRABOWSKI.
